UNITED STATES PATENT OFFICE.

ROBERT V. PROCTOR, OF YOUNGSTOWN, OHIO, ASSIGNOR TO THE COMMERCIAL SHEARING & STAMPING COMPANY, OF YOUNGSTOWN, OHIO, A CORPORATION OF OHIO.

CASTING BAT AND METHOD OF FORMING ARTICLES.

Application filed November 6, 1925. Serial No. 67,333.

The present invention relates broadly to the art of forming bonded articles of abrasive materials, such as grinding wheels, disks and the like, or to the formation of porcelain 5 ware, vases, pottery and the like, and more particularly to an improved bat adapted for the manufacture of such articles.

At the present time grinding wheels, for example, are usually formed by making a 10 bat of plaster of Paris or other suitable material, which serves as a support for the wheel during the casting and drying operations. A thick sheet of absorbent paper or similar material is then placed on the bat, 15 after which an open ended sheet metal cylinder of somewhat greater diameter than the diameter of the proposed wheel is stood on end on the absorbent paper, either before or after lining the same with an absorbent material similar to that placed on the bat. 20 Thereafter the wet mixture of abrasive material is poured into the cylinder to a depth somewhat greater than the desired thickness of the finished wheel.

25 The bats with the wheels on them are then placed over steam coils and allowed to dry slowly for a length of time dependent largely upon the bulk of the wheel. Part of the mixture is taken off the top to bring 30 the thickness of the wheel more nearly to the required point, and as soon as the wheel is set enough to stand alone, the cylinder of sheet metal is removed to permit the moisture to evaporate from the wheel with 35 greater rapidity. It will be apparent that the bat itself conducts some moisture from the wheel, its rate of conductivity or moisture dissipation naturally being considerably less than the rate of moisture dissipation 40 from the sides directly into the air, whereby there is always a cone-shaped zone of material at the base of the wheel, as it lies on the bat, which has a relatively high moisture content even when the rest of the 45 wheel is nearly dry. After the wheels have been allowed to remain in the open until they are dry enough to be handled, the bats and wheels are placed on cars or racks and placed in dryers heated to about 220 degrees 50 until the wheel is dry enough to be cut down to the proper size and shape ready for forming. Inasmuch as the thickness of the bat is determined to a very large extent by the size of the bat and the weight of the wheel, 55 it will be apparent that with large bats and

large wheels the complications during drying are considerably increased.

One of the objects of the present invention is to provide an improved bat and method of forming articles of the character 60 referred to, whereby greater uniformity of drying is obtained with a consequent improvement in the quality of the articles produced.

In the accompanying drawings there are 65 shown, for purposes of illustration only, certain preferred embodiments of the present invention, it being understood that the drawings do not define the limits of my invention as changes in the construction and operation disclosed therein may be made without departing either from the spirit of 70 the invention or the scope of my broader claims.

In the drawings—

75 Figure 1 is a vertical sectional view through a plurality of bats constructed in accordance with the present invention having grinding wheels supported thereon and stacked to facilitate drying;

Figure 2 is a bottom plan view of one of the bats illustrated in Figure 1, the supporting legs, however, being omitted;

Figures 3, 4 and 5 are top plan views on a reduced scale illustrating respectively different arrangements of bats; and

Figure 6 is a vertical sectional view, similar to Figure 1, illustrating a modified form of bat.

In carrying out the present invention, 90 there may be provided a pan-shaped metallic casing 2 having a bottom 3 so shaped as to provide a cavity of either less or the same depth adjacent the center of the casing than adjacent the edge thereof. The 95 edge 4 is in turn preferably of inwardly converging nature so as to overhang a portion of the pan cavity. The bottom 3 is preferably provided with a plurality of openings 5 to increase the possibility of 100 air contact with the material in the casing, and the edge may be provided with any desired number and arrangement of handles 6 as illustrated in Figures 3, 4 and 5.

After the casing has been completed, it 105 is filled with a suitable composition, preferably plaster of Paris 7 which interlocks with the casing by reason of the openings 5 and the inwardly extending edge 4. After the filling 7 has solidified, the bat is ready 110

for use in accordance with present day practices.

A sheet of absorbent paper or similar material 8 may now be placed on the bat and 5 a cylinder 9 with an absorbent lining 10 is then supported on the absorbent material 8. The mixture 11 for the wheel, or other article, which mixture may comprise abrasive material, clay and water, or other suitable ingredients, is then poured into the lined cylinder whereupon the article is ready for the drying operation as before set forth.

If desired, the bat casing may be provided with legs 12 adapted to support the bats in spaced relation to a floor or other surface to permit the circulation of air to the openings 5, or to permit the bats to be stacked in superimposed relationship.

20 By reason of the use of a reinforced bat of the general nature referred to, the bat may obviously be made of much less thickness for a given sized article than has heretofore been considered feasible. This of it- 25 self insures a more rapid drying of the bottom of the article. By reason of the variations in the thickness of different portions of the bat with the portion of less thickness adjacent the center, the central 30 bottom portion of the article is permitted to dry proportionately faster with respect to moisture dissipation through the bat 7 than surrounding portions, thereby insuring more nearly uniform drying conditions.

35 This is true for the reason that such surrounding portions in addition to throwing off moisture through the bat, also give out moisture laterally directly through the air. In actual operation it has been found that 40 greatly superior results can be obtained by the use of a bat of the general nature referred to.

Preferably, each bat will be of the general construction illustrated in Figure 1 45 with a gradually decreasing thickness from the edge inwardly, the variation in thickness being roughly in accordance with the natural tendency of the bat to dissipate moisture from an article supported thereon.

50 In Figure 6, however, there is illustrated a modified embodiment of the invention in which the bat is of sectional construction, either as to the casing alone, or as to both the casing and plaster of Paris filling, with 55 successive sections inwardly of decreasing thickness. In this form of the invention there is illustrated an outer annular or rectangular section 13, an intermediate section 14 and a central section 15. It will 60 be apparent that the sections may all be of standard dimensions whereby any desired number may be assembled at will to thereby produce bats of different sizes and shapes. In this manner the necessity of 65 constructing a large number of separate bats

of a given size is obviated. The sections may be suitably shaped, as by providing offsets 16, whereby upon assembly the sections will be automatically maintained in the desired relative positions.

70 It will be understood that the variations in the thickness of the bat may be different for different articles or different types of articles in order to bring the thinnest portion adjacent the part of the article in 75 which the most rapid dissipation of moisture is deemed desirable. In this manner, the thickness of the bat may be effectively utilized for controlling the drying of the articles being produced thereon.

80 It will also be apparent to those skilled in the art that the shape or configuration of the bat may be varied at will within the spirit of the present invention. For example, the bat may be oval, rectangular or 85 the like, to permit it to readily accommodate a plurality of cylinders at one time.

90 While the invention has been particularly described in connection with the manufacture of grinding wheels, it will be understood from the specification that other articles and shapes may be similarly manufactured, and that porcelain ware, vases, pottery and other articles of clay or the like may be similarly produced.

95 Certain advantages of the invention arise from the provision of a bat having different portions of different thickness, and particularly in constructions of this character in which the portion of less thickness is adjacent the center of the bat.

100 Other advantages arise from the provision of a reinforced bat whereby the thickness thereof as a whole may be materially reduced.

105 Still other advantages arise from the provision of a sectional bat or bat casing in which the respective sections are of decreasing depth inwardly.

I claim:

110 1. As an article of manufacture, a reinforced bat comprising a body of plaster of Paris material and reinforcing means therefor, substantially as described.

115 2. As an article of manufacture, a reinforced bat having different portions thereof of different thickness, substantially as described.

120 3. As an article of manufacture, a sectional bat having different portions thereof of different thickness, substantially as described.

125 4. As an article of manufacture, a bat comprising a plurality of separable sections, substantially as described.

130 5. As an article of manufacture, a bat comprising a plurality of separable sections with different sections of different thickness, substantially as described.

6. As an article of manufacture, a bat

casing having an upturned edge, said casing and edge defining a cavity having different portions of different depths, substantially as described.

5 7. As an article of manufacture, a bat casing having an upturned edge, said casing and edge defining a cavity having different portions of different depths, with the shallowest portion adjacent the center 10 of the bat, substantially as described.

8. The method of drying articles of a plastic composition, comprising providing a moisture dissipating body, constructing said

body to provide portions of varying thickness in accordance with the desired rate of 15 moisture dissipation therethrough, and then supporting the article to be dried on said body.

9. As an article of manufacture, a reinforced bat comprising a body of porous 20 material, and reinforcing means for said body, substantially as described.

In testimony whereof I have hereunto set my hand.

ROBERT V. PROCTOR.
